PENCIL HOLDER

Filed Dec. 22, 1930

Inventor:
Lydia Schermund.

UNITED STATES PATENT OFFICE

LYDIA SCHMERMUND, OF ST. LOUIS, MISSOURI

DESIGN FOR A PENCIL HOLDER

Application filed December 22, 1930. Serial No. 38,084. Term of patent 3½ years.

To all whom it may concern:

Be it known that I, LYDIA SCHMERMUND, a citizen of the United States, residing at 5753 St. Louis Avenue, in the city of St. Louis and State of Missouri, have invented a new, original, and ornamental Design for a Pencil Holder, of which the following is a specification, reference being had to the accompanying drawing, forming a part thereof.

The figure is a plan view of a pencil holder, showing my new design.

I claim:

The ornamental design for a pencil holder as shown.

LYDIA SCHMERMUND.
